ILLUMINATING COSMETIC MIRROR

Donald P. Stahl, North Bellmore, N.Y., assignor to Telecommunication Industries, Incorporated, Farmingdale, N.Y.

Filed Dec. 18, 1970, Ser. No. 26,566

Term of patent 14 years

Int. Cl. D28—03

U.S. Cl. D86—10 H

FIG. 1

FIG. 2

FIG. 4

FIG. 1 is a perspective view of an illuminating cosmetic mirror showing my new design;

FIG. 2 is a front elevational view of the mirror in an alternate position;

FIG. 3 is a side elevational view; and

FIG. 4 is a rear elevational view.

I claim:

The ornamental design for an illuminating cosmetic mirror, substantially as shown and described.
